[57] CLAIM

The ornamental design for a vehicle sunshield, as shown and described.

DESCRIPTION

FIG. 1 is a perspective view of a vehicle sunshield showing my new design;

FIG. 2 is a front view;

FIG. 3 is a bottom view;

FIG. 4 is a rear view;

FIG. 5 is a top view;

FIG. 6 is a right side view;

FIG. 7 is a left side view; and,

FIG. 8 is a front perspective view thereof on a reduced scale in position of use on a vehicle which is shown and described in broken lines for illustrative purposes only and forms no part of the claimed design.

FIG. 1

FIG. 2

FIG. 3

FIG. 7

FIG. 6

FIG. 8
